UNITED STATES PATENT OFFICE.

JAMES J. LONERGAN, OF CLEVELAND, OHIO.

DESIGN FOR A CATCH-BASIN.

SPECIFICATION forming part of Design No. 30,054, dated January 24, 1899.

Application filed November 8, 1898. Serial No. 695,904. Term of patent 7 years.

To all whom it may concern:

Be it known that I, JAMES J. LONERGAN, a citizen of the United States, and a resident of Cleveland, county of Cuyahoga, State of Ohio, 5 have invented and produced a certain new and original Design for Catch-Basins, of which the following is a specification, reference being had to the accompanying drawings, forming part thereof.

10 Figure 1 is a plan view of a catch-basin, showing my new design. Fig. 2 is a side view thereof; and Fig. 3 is a sectional view taken on line $x-x$, Fig. 1.

As shown in the drawings, the leading or 15 material feature of my design consists in the external angular shape of the basin A and in the pendent portion of the top B, taken in connection with the straight overhanging edge of the top C. The exterior is angular,

and, as shown, the upper portion is rectangular and the lower portion polygonal. The top is perforated at D. A circular flange is shown at the base of the basin. The pendent portion of the top is shown centrally depressed at I and turning sharply downward 25 at H.

Having described my invention, what I claim as new, and desire to secure by Letters Patent, is—

The design for a catch-basin as herein shown 30 and described.

Signed by me, at Cleveland, Ohio, this 26th day of October, A. D. 1898.

JAMES J. LONERGAN.
